UNITED STATES PATENT OFFICE.

TALEBOT G. MARTIN, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Original application filed March 15, 1921, Serial No. 452,468, now Patent No. 1,539,132, dated May 26, 1925. Divided and this application filed April 6, 1925. Serial No. 20,885.

The present invention relates in general to automatic telephone systems, but more especially to large automatic systems which employ both primary and secondary line switches for the purpose of connecting calling lines with idle first selector switches; and the object of the invention is the provision of various improvements in a system of this kind which tend to increase its utility and commercial success. In particular the invention contemplates the use of secondary line switches of the rotary type, and arrangements are shown whereby such switches may be used to advantage in conjunction with primary line switches of the well known Keith or plunger type. Many of the features, however, are not limited to this arrangement.

A special object is the provision of novel and improved auxiliary circuits for a primary and secondary line switch system. These circuits have to do particularly with an arrangement for making a group of secondary switches busy to primary switches in case all trunks accessible to such secondary switch become busy, or in case a fuse supplying battery current to such secondary switches should blow. Arrangements are also provided for picking up the plungers of the primary switches under these circumstances and for testing the pick-up circuit in case it should get out of order. In connection with the primary line switches means is provided for preventing the operation of any switch of a group in case all the trunks accessible to such group are busy and for signalling an operator if a subscriber calls while his line switch is inoperative.

This application is a division of my prior application, Ser. No. 452,468, filed March 15, 1921, patented May 26, 1925, No. 1,539,132, in which the above features are described and illustrated but not claimed.

The foregoing features and others not now specifically mentioned will be described hereinafter with reference to the accompanying drawings, which show sufficient of the apparatus in an automatic telephone system to enable the invention to be explained and understood.

Referring to the drawing, the reference character A indicates an automatic telephone substation of the ordinary type hav-

ing the usual talking instrumentalities and a calling device S for controlling the automatic switches at the exchange. The line conductors 11 and 12 terminate at the exchange in the individual line switch C, which is a line switch of the well known Keith or plunger type, and hence will not need to be described in detail. Briefly stated, the function of the line switch C is to extend the associated line when calling to an idle trunk line. In accordance with the usual practice, the lines entering the exchange are divided into groups, and all of the line switches associated with the lines in each group may be controlled in their trunk selecting operations by a common master switch. The master switch which is associated with the group which includes the line switch C is shown in the lower left-hand corner of the sheet and is indicated by the reference character E. This master switch is of the well known solenoid type such as is in common use in the automatic telephone exchanges throughout the country.

Secondary line switches are employed in the present system and accordingly the trunk lines from the primary line switch-boards will extend to secondary line switches rather than to first selector switches. The arrangement of the trunking between the primary and secondary line switch-boards is well understood. There may be a plurality of groups of secondary line switches and each group of primary line switches will have outgoing trunks extending to secondary line switches in each secondary group, so that any calling subscriber will be given access to the trunk lines outgoing from all of the secondary groups. In this manner a large number of first selectors, say one hundred or more, may be combined in one large group thus securing an increased trunking efficiency. The advantages gained by the use of secondary line switches, however, are well known and need not be discussed in detail.

One of the trunk lines outgoing from the primary group which includes the line switch C is shown in the drawing, and extends to the secondary line switch D. The line switch D is of the well known rotary type, having wipers which normally stand on the trunk line last used, and which move in a forward direction only. As usually

constructed, this line switch has a semi-circular bank comprising twenty-five contact sets and double wipers standing at an angle of 180 degrees apart.

5 The jack J and the lamp L are provided for a particular purpose to be explained hereinafter and are located at the wire chief's, or complaint operator's desk. This jack is individual to the particular primary 10 group which includes the line switch C, and there may be a similar jack for each of the other primary groups. There are a number of relays at the right of the drawing which have certain functions to perform when all 15 of the trunk lines outgoing from the secondary line switch group which includes the line switch D become busy, and at other times. It will be convenient, however, to go into this later on during the explanation of 20 the operation of the system.

Having described the apparatus involved briefly, its operation will now be described more in detail with a view to pointing out the particular features of novelty disclosed 25 herein. For this purpose it will be assumed that the subscriber at substation A desires to call some other subscriber in the system, and the operation of the primary and secondary line switches C and D in connecting 30 the line of substation A to a trunk line extending to a first selector switch will be described. When the receiver is removed at substation A a circuit is completed over the line conductors 11 and 12 for the line relay 35 16 of the line switch C. Upon energizing, the line relay 16 closes a circuit for the pull down winding 18 of the line switch at armature 25. Upon energizing, the pull down winding operates both the cut-off armature 40 24 and the plunger arm 23, the former being effective to disconnect the line conductors 11 and 12 from the winding of the line relay and from the grounded common conductor 46, respectively; while the latter forces the 45 bank springs 30, 31, 32, and 33 into engagement with contacts 34, 35, 36, and 37, respectively. By the engagement of bank springs 30 and 33 with contacts 34 and 37, the line conductors 11 and 12 are extended into connection with the trunk line conductors 40 and 42, and a circuit is accordingly completed for the line relay 50 of the secondary line switch D. The line relay 50 is accordingly energized and at its armature 53 closes 50 a holding circuit for the line switch C, which may be traced from ground by way of the working contact of armature 53 and the said armature, normally closed contact springs controlled by armature 58, release 55 trunk conductor 41, contact 35, bank spring 31, and the holding winding 17 of the line switch C to battery. This holding circuit is established before the slow acting line relay 16 of the line switch has time to de- 60 energize and is effective to retain the plunger 65

arm 23 and the cut-off armature 24 in operated position. A ground potential is also placed on the private normal conductor 15 which extends to multiple test contacts on the banks of the connectors which have access to the line of substation A, whereby the line is guarded against intrusion in the customary manner. Another circuit closed by the operation of the line switch C is completed by the engagement of bank springs 70 32 with contact 36. This places a ground on conductor 43 and a circuit is thus completed by way of the master switch test wiper 108 and the left-hand winding of the starting relay 100 to battery. Relay 100 is accordingly energized and at its left-hand armature completes a circuit for the locking relay, or magnet 101. As is well understood, when the locking relay is energized it releases the master switch shaft (controlling 75 all the idle line switch plungers) and the shaft instantly turns in a counter clock-wise direction under control of a governor, the operating force being supplied by a heavy spring under tension. The test wipers 108 and 107 are attached to this shaft, from which it will appear that these test wipers will immediately be moved off from their associated tenth test contacts and into engagement with the associated ninth test contacts. Assuming that the ninth trunk line is idle, there will be no ground potential on the ninth test contacts, the starting relay 100 will deenergize to open the circuit of the locking relay 101, and the latter relay will 80 deenergize to again lock the master switch shaft. It may be pointed out in this connection that when the locking relay 101 is energized it closes a circuit for the "open main" relay 103 which disconnects the common conductor 44 from the non-grounded pole of the battery. This is to prevent the operation of any other line switches while the master switch shaft is being moved from one trunk to another by the master switch. 85

Continuing now with the operation of the secondary line switch D, when the line relay 50 is energized as explained hereinbefore, it closes a circuit at its armature 54 which includes the winding of the switching relay 51 and the winding of the stepping magnet 52 in series, while at the same time by means of armature 55 the test wiper 66 is connected to this circuit at a point between the said relay and the said magnet. The operation now depends upon whether the trunk line with which the line switch wipers are associated is busy or idle. If this trunk line is busy there will be a ground potential on the test contact engaged by test wiper 66, such as test contact 69 for example, the switching relay 51 will be short circuited, and the stepping magnet 52 being supplied with direct ground via the test wiper will operate in the manner of a buzzer 90

125

130

to advance the switch wipers step by step in search of an idle trunk line. This movement will continue as long as the test wiper 66 continues to engage grounded test contacts.

5 When the wipers arrive at an idle trunk line, which we may assume is the trunk line comprising conductors 77, 78, and 79, the test wiper 66 will find no ground potential on the test contact 72, the rotation of the switch 10 will cease and the switching relay 51 being no longer short circuited will energize in series with the stepping magnet 52, the latter remaining inoperative on account of the high resistance of the switching relay. Upon 15 energizing, relay 51 connects the incoming release trunk conductor 41 to the test wiper 66 by means of armature 58, and at armature 57 connects its own lower terminal to the now continuous conductor extending from 20 the test wiper 66 back over conductor 41 to the line switch C. The line relay 50 being still energized, the test wiper 66 is connected to ground by these operations in order to render the selected trunk line busy. In addition to the foregoing, at armatures 56 and 25 59 relay 51 disconnects the incoming trunk conductors 40 and 42 from the winding of the relay 50 and from ground, respectively, and extends them by way of wipers 65 and 30 67, bank contacts 71 and 73 and conductors 77 and 79 to the line relay of the first selector switch in which the selected trunk line terminates. Although this switch is not shown, its operation is well understood and 35 it will be sufficient to state that the line relay of the selector is energized over the circuit of the calling line and closes a circuit for the associated slow acting release relay. The latter relay, upon energizing, places a 40 ground potential upon the release trunk conductor 78, thereby establishing a holding circuit for the switching relay 51 of the secondary line switch D, and for the holding winding 17 of the primary line switch C. 45 This holding circuit, it will be understood, is established before the slow acting line relay 50 has had time to deenergize.

The remainder of the operations in which the calling subscriber controls the first selector taken for use, and a plurality of other automatic switches through the medium of his calling device S, to complete the connection to the desired called line, are well understood and as they have nothing special 50 to do with the present invention, these operations will not be further considered, except to say that when the calling subscriber has finished talking, the restoration of his receiver to the switch-hook causes the automatic switches to restore to normal with the result that ground is disconnected from the release trunk conductor 78. This operation breaks the holding circuit for the primary and secondary line switches C and D and the 55 said switches are restored to normal position,

it being understood that the restoring operation at the secondary line switch D consists merely in the deenergization of the switching relay 51.

Having described the system in a general way, it will be convenient now to explain the various features which I have incorporated therein with a view to enhancing its commercial success. One of these features is a new arrangement for making all of the trunk lines incoming to a group of secondary line switches busy whenever all of the trunk lines outgoing from such secondary group become busy. It will be appreciated that it is necessary to do this, since if calls were permitted to arrive at a group of secondary line switches when no trunks were available outgoing from such group, it would inevitably happen that such calls would be lost, i. e., they could not be successfully completed. In order to accomplish the desired result, and considering the group of secondary line switches which include the line switch D, a series of chain relays are provided, one for each outgoing trunk, and these 75 chain relays are connected, one to each of the release trunk conductors. It follows that as fast as the trunk lines become busy the chain relays will be energized, and when all of the trunk lines are busy all of the 80 chain relays will be energized, with the result that ground is placed on the conductor 82, thus closing an energizing circuit for the relay 83. Upon energizing, relay 83 closes at armature 89 a circuit for relay 85, which 85 upon attracting its armatures connects ground to the conductor 93'. The release trunk conductor 41 of the trunk line which terminates in the secondary line switch D is normally connected to the conductor 93', and if the 90 trunk line is not otherwise engaged it is made busy anyway. Relay 85 may be a large multiple contact, or gang relay, or a number of relays connected in series or parallel may be used; at any rate, at the same time that conductor 93' is grounded similar conductors extending to all of the remaining secondary line switches in the same group are grounded also, thus making all of the 95 trunk lines incoming to the group in question busy. 100 As a further result of the energization of relay 83, upon all of the trunk lines becoming busy the conductor 92 is grounded momentarily for the purpose of operating the master switches in all of the primary groups from which trunk lines lead to the particular secondary group in question. The slow 105 acting relay 84 is normally energized, but when relay 83 attracts its armature the circuit of relay 84 is broken. Relay 84, however, does not retract its armature immediately and in the meantime relay 83 places ground on conductor 92 by means of its 110 armature 88. The grounding of conductor 92 115 120 125 130

is only momentary as ground is taken off at armature 86 as soon as relay 84 falls back. When conductor 92 is grounded in this manner a circuit is completed through contacts 5 of key K² to the common conductor 200 and thence by way of the normally closed switch S', contacts of key K¹, conductor 94, and the winding of relay 102 to battery. Upon energizing, relay 102 establishes a locking circuit for itself at its armature 120 and at its armature 121 closes the circuit of the locking relay 101. Upon energizing, relay 101 closes a circuit for the "open main" relay 103 and at the same time unlocks the master switch shaft mechanically so that it is free to move to the left, or in a counter clock-wise direction, under control of the main spring and governor, as previously explained. Since relay 102 has been locked in energized position, this movement will continue until the wipers 107 and 108 arrive at the first test contacts in their respective banks at which time the line switch plungers will be opposite the first trunk. The arm 122 now closes 15 contact springs 124 and 125, thus completing a circuit for relay 104. When relay 104 attracts its armature, the armature is locked in operated position behind the tooth on spring 126 so that the relay remains in operated position after its energizing circuit is broken. The energization of relay 104 breaks the locking circuit of relay 102, permitting this relay to fall back, and also closes a new circuit for the locking relay 101, 20 in order that this latter relay may be held up after the relay 102 has deenergized. In addition, relay 104 closes a circuit for the solenoid 106. Upon the energization of the solenoid, the master switch shaft is rotated by a continuous movement in a clock-wise direction until all of the plungers are lined up opposite the tenth trunk, wipers 107 and 108 being restored to the position shown in the drawing. The arm 123 now disengages 25 spring 126 from the armature of relay 104 and this armature is released to break the circuit of the solenoid 106 and the circuit of relay 101. Relay 101 now deenergizes and locks the shaft in position opposite the tenth trunk. There is nothing particularly new in most of these operations at the master switch and they have been described merely in order to make clear the purpose of placing momentary ground on conductor 92 under the circumstances stated. Obviously when the primary master switches are operated, any line switch plungers which happen to be disengaged from the shaft are "picked up" and are again brought under the control of the master switch so that there will be no danger of any of them being plunged in on busy trunk lines.

Another feature is a provision for making all the incoming trunks at a group of secondary line switches busy, and for operating

the primary master switches, as described in the foregoing, in case the main fuse which supplies operating battery to the line switches of the group should blow. Considering this feature a little further, the reference character 96 indicates the main fuse which supplies operating current to all of the secondary line switches which are associated with the line switch D in the same group. It will be understood, of course, that in practice relay 50 and the stepping magnet 52, instead of being connected direct to the ungrounded pole of the battery, are connected thereto by way of the fuse 96, as are the relays 83 and 84. Now, if this fuse 30 should blow for any reason all of the secondary line switches in the group will at once become inoperative, and it will clearly become necessary to render all the incoming trunk lines busy, and also to operate all the primary master switches in order to pick up any line switch plungers which may happen to be standing on trunk lines extending to the secondary group in question. This is accomplished as follows: When the fuse 90 blows, relay 84 will deenergize and by means of its armatures 86 and 90 circuits are closed simultaneously for energizing relay 85, and for placing a ground on conductor 92. Relay 85 is energized, grounding conductor 93 and similar conductors in order to make the incoming trunk lines busy, while at armature 91 this relay removes ground from conductor 92. Conductor 92 is thus grounded momentarily, as in the case previously explained, and by the consequent locking up of relay 102 and similar relays associated with the other primary master switches, all of these master switches are operated as and for the purpose already set forth.

The keys K² and K¹, together with a plurality of other similar keys, may be located on a test panel in some convenient place in the switch room, and are provided for the purpose of enabling an attendant, or switch-board man, to locate trouble on the common conductor 200 and its various branches. There may be as high as half a dozen groups of secondary line switches, and twenty-five or more groups of primary line switches, from which it will be clear that there may be six branches corresponding to branches 92 and 93, and twenty-five or more branches corresponding to the branch 94, and it will be appreciated that if any one of these branches should become permanently grounded in some way, the consequences would be extremely serious. The test keys are provided, therefore, to enable the attendant to quickly locate such trouble if it should occur, which is accomplished by operating the keys successively and observing the sound of the buzzer 95. As soon as any particular key is operated, the branch associated with such key is disconnected from the common 120

conductor 200, and the latter conductor is connected with the buzzer. If it should happen that the branch associated with the operated key is the one which is grounded, the 5 common conductor will now be clear and the buzzer will be silent. However, if the wrong key has been operated, the common conductor will still have a ground on it and the buzzer will operate, indicating to the 10 attendant that the trouble has not yet been located. Obviously if the keys are operated in quick succession a few seconds only will be required to locate the particular branch which is in trouble.

15 The key K⁴ is known as an emergency "pick up" key, and may be mounted on the test panel with the keys just described. It is useful to the attendant for trying the operation of the primary master switches, 20 and may also be used in case the regular circuits for automatically operating these master switches should get out of order. The exchange is always equipped with various supervisory signals and alarms which indicate the blowing of fuses, or the busy condition of trunk groups, etc. The attendant is thus, at all times, aware of the condition of the equipment and in case some of the 25 automatic devices fail to perform their functions he may accomplish the desired results by means of the emergency key.

As stated hereinbefore, a number of meters are provided for recording certain events occurring during the operation of the 30 system, and these meters and their functions will now be explained. The "peg count" meter M² will be considered first. It will be observed that the common conductor 44, which supplies battery to the pull in 35 windings of all the primary line switches of the group which includes the line switch C, includes the winding of the low resistance relay 112, and it will be clear, therefore, that whenever one of these line switches 40 is operated relay 112 will be operated also. Each time relay 112 operates it closes a circuit for the meter M², and this meter, therefore, will register the total number of calls 45 outgoing from the group in question.

50 The meter M¹ is the "all trunk busy" meter, which functions as follows: In case all of the trunks outgoing from the primary line switch group are busy all of the test contacts in the bank associated with test 55 wiper 107 will be grounded, and the starting relay 100 will remain energized as long as this condition continues. When relay 100 is energized it closes a circuit for the locking relay 101 in order to initiate the operation 60 of the master switch, as explained before, and it also closes a parallel circuit through the relay 111. This latter relay is a special relay constructed as shown in the pending application of John Erickson, Serial No. 65 348,548, filed December 31, 1919. When

its armature is attracted a circuit is completed for meter M¹, but at the same time a pendulum is set in motion which in vibrating rapidly interrupts the circuit of the said meter and thus for a certain definite time 70 prevents it from operating. A relay of this type is used so that in the ordinary operation of the system the meter M¹ will not be caused to register even though relay 111 is momentarily energized from time to time. The 75 time interval of the pendulum controlled by relay 111 is of such duration that the master switch can operate in two complete cycles, and thus the meter will not be operated during the ordinary operation of the master 80 switch in stepping from trunk to trunk, or even when the master switch moves the plungers from the first to the tenth trunk, while if all the trunks are busy and the master switch is in continuous operation, the 85 meter will be caused to register.

The remaining meter M³ is provided for registering calls which fail because no outgoing trunks are available. It will be observed that the common conductor 46, to 90 which the lower side of each subscriber's line is connected, extends to the winding of relay 110 to ground. Relay 110, however, is normally short circuited at the armature of the starting relay 100, and it follows, therefore, 95 that in the ordinary operation of the system when a subscriber removes his receiver and operates his line relay, such as the line relay 16, relay 110 will not be energized. In case all the trunks are busy, however, the 100 starting relay 100 will be held up continuously and relay 110 will not be short circuited. Under these circumstances, if another subscriber should attempt to make a call, when he removes his receiver, relay 110 105 will be energized. This relay is of very high resistance and prevents the line relay of the calling line from pulling up at this time. Upon energizing, relay 110 closes a circuit for the relay 109, which is a relay 110 equipped with a pendulum device the same as relay 111. If the starting relay 100 does not deenergize before the expiration of a definite time interval, relay 109 will permanently close the circuit of the meter M³ 115 in an obvious manner and the said meter will be caused to register.

When the circuits are connected as shown in the drawing, if the starting relay falls back before meter M³ has operated in the 120 case just described, relay 110 will immediately be short circuited again and it will fall back to break the circuit of relay 109 which in turn will restore its armature and prevent the meter M³ from being operated, as 125 explained in the preceding paragraph; but if the jumper containing terminals 130 and 131 is cut the operation will be different. With this arrangement of the wiring the lamps, such as the lamp L at the wire chief's, 130

or complaint operator's desk, are preferably inserted in their jacks and when the relay 110 operates in response to a call, during a time when all the trunks are busy, it will 5 open the short circuit around its winding and its upper armature so that it will not be restored until the calling subscriber replaces the receiver, even though in the meanwhile one or more of the outgoing trunk lines 10 should become idle. At the same time, relay 110 closes a circuit for the lamp L and thus notifies the wire chief that some subscriber in the group associated with said lamp is trying to call under circumstances which are 15 bound to render his attempt unsuccessful, and the wire chief will, therefore, plug into the jack J with a cord circuit, with which his position is provided, and will talk to the subscriber and advise him to try the number 20 over again after a few minutes. Relay 110 it may be mentioned is made slow to energize by providing it with a copper slug on its armature end. This is done so that if someone should attempt to call during a momentary energization of the starting relay 100, while the master switch is stepping from 25 trunk to trunk, the relay 110 will not energize and will not become locked up under these circumstances.

Having described my invention, what I consider to be new and desire to have protected by Letters Patent will be pointed out in the appended claims.

What I claim as my invention is:

1. In a telephone system subscribers' lines, trunk lines, groups of primary line switches and a group of rotary secondary line switches for extending calling lines to idle trunk lines, there being a secondary trunk line extending from each primary group to one of said secondary line switches, chain relays associated with said first named trunk lines, each relay being energized when the associated trunk becomes busy, a relay normally deenergized, means controlled by said chain relays when all the associated trunks become busy for causing said normally deenergized relay to energize, and means controlled by the energization of said relay for 45 making all of said secondary trunk lines busy, said means including circuits extending through contacts on relays in each of the secondary line switches.

2. In a telephone system, subscribers' lines, trunk lines, groups of primary line switches and a group of secondary line switches for extending calling lines to idle trunk lines, there being a secondary trunk line extending from each primary group to one of said secondary line switches, a main fuse supplying operating battery to the secondary line switches of said group, a relay normally energized by current supplied through said fuse, and circuit connections for making all 60 of said secondary line switches busy in case

said relay is deenergized by the blowing of said fuse.

3. In a telephone system, subscribers' lines, trunk lines, groups of primary line switches and a group of secondary line switches for 70 extending calling lines to idle trunk lines, there being a secondary trunk line extending from each primary group to one of said secondary line switches, a master switch in each primary group controlling the associated 75 primary line switches, a main fuse supplying operating current to the secondary line switches of said group, a relay normally energized by current supplied through said fuse, and circuit connections for operating 80 all of said master switches in case said relay is deenergized by the blowing of said fuse.

4. In a telephone system, subscribers' lines, trunk lines, groups of primary line switches and groups of secondary line switches for 85 extending calling lines to idle trunk lines, a master switch for controlling each group of primary line switches, a common conductor branching at one end to each primary group and at the other end to each secondary group, 90 means associated with each secondary group for placing a potential on the branch extending thereto in case all the trunk lines accessible to the switches in such group become busy, and means controlled over each 95 primary branch for operating the associated master switch.

5. In a telephone system, subscribers' lines, trunk lines, groups of primary line switches and groups of secondary line switches for 100 extending calling lines to idle trunk lines, a master switch for controlling each group of primary line switches, a common conductor branching at one end to each primary group and at the other end to each secondary group, 105 means associated with each secondary group for placing a potential on the branch extending thereto in case all the trunk lines accessible to the switches in such group become busy, means controlled over each primary 110 branch for operating the associated master switch, a signal, and test keys in the several branches for use in conjunction with said signal to locate an accidental potential on any branch.

6. In a telephone system, subscribers' lines, trunk lines, groups of primary line switches and groups of secondary line switches for 115 extending calling lines to idle trunk lines, a master switch for controlling each group of primary line switches, a common conductor branching at one end to each primary group and at the other end to each secondary group, 120 means associated with each secondary group for placing a potential on the branch extending thereto in case all the trunk lines accessible to the switches in such group become busy, means controlled over each primary 125 branch for operating the associated master switch, and an emergency key manu- 130

ally operable to place a potential on said common conductor, whereby said master switches and the operating circuits therefor may be tested by an attendant.

- 5 7. In a telephone system, a group of subscribers' lines, a group of trunk lines, individual line switches for extending calling subscribers' lines to idle trunk lines, a relay, circuit connections for operating said relay 10 in case a line should attempt to call while all of said trunk lines are busy, a manual jack common to all of said lines, and a signal associated with said jack and controlled by said relay.
- 15 8. In a telephone system, a group of subscribers' lines, a group of trunk lines, individual line switches for extending calling subscribers' lines to idle trunk lines, means dependent on the busy condition of all trunk 20 lines for preventing the operation of any line switches, and means whereby in case a call is attempted while all the trunks are busy the possibility of operating any of said line switches is made dependent on the continuation of the attempted call.

9. In a telephone system, a group of subscribers' lines, a group of trunk lines, line switches individual to said subscribers' lines arranged to establish connections between 30 said subscriber's lines and said trunk lines, and means dependent on the busy condition of all the said trunk lines when a call is initially attempted to prevent the subsequent operation of any of said line switches.

- 35 10. In a telephone system, a group of subscribers' lines, a group of trunk lines, line switches individual to said subscribers' lines arranged to establish connections between said subscribers' lines and said trunk 40 lines, and means initially operated when a call is attempted and all trunks are busy but maintained operated by a line attempting to make a call, said means when operated preventing the operation of any of 45 said line switches.

11. In a telephone system, subscribers' lines, a group of plunger type primary line switches, trunk lines accessible to said switches and leading to groups of rotary 50 secondary line switches, different trunk lines accessible to each of the groups of secondary switches, a master switch arranged to move the plungers of said primary switches opposite a different trunk line 55 when the trunk line opposite which they rest is connected to give a busy indication, a relay operated when all the trunks accessible to a secondary switch are busy, and a circuit including two branches, one of 60 which extends through a front contact on said secondary switch and the other branch through a front contact on said relay and a back contact on said secondary switch, for giving a busy indication.

- 65 12. In a telephone system, a primary line

switch, a secondary line switch accessible to said primary switch, a source of E. M. F. for operating said secondary line switch, and means arranged to cause said secondary switch to give a busy indication to said primary switch if the source of E. M. F. ceases to supply E. M. F. to said secondary switch. 70

13. In a telephone system, a group of switches, a second group of switches, trunks accessible to the second group of switches, 75 each of the switches in the second group being accessible to each of the switches in the first group, means for indicating to said first mentioned switches a busy condition of said switches of the second group, connections including a battery for operating the second group of switches, and means common to all the switches in the secondary group for giving the busy indication if the battery fails to supply E. M. F. to the switches. 80

14. In a telephone system, a group of switches, a second group of switches, trunks accessible to the second group of switches, each of the switches in the second group being accessible to each of the switches in the first group, means for indicating to said first mentioned switches a busy condition of said switches of the second group, connections including a battery for operating the second group of switches, and means common to all the switches in the secondary group for giving the busy indication if the battery fails to supply E. M. F. to the switches. 85

15. In a telephone system, wherein a group of switches having access to a number of trunks are themselves accessible to another switch, and each of the switches of the group is provided with means for indicating a busy condition to said other switch, and a source of E. M. F. is provided for operating the group of switches, means common to the group of switches arranged to give the busy indication if the E. M. F. ceases to be supplied. 100

16. In a telephone system, wherein a group of switches having access to a number of trunks are themselves accessible to another switch, and each of the switches of the group is provided with means for indicating a busy condition to said other switch, and a source of E. M. F. is provided for operating the group of switches, means including a relay common to the group of switches and normally energized from said source of E. M. F. arranged to give the busy indication when deenergized, and means for deenergizing said relay when all the trunks accessible to the group of switches are busy. 115 120

17. In a telephone system, a relay normally shunted to prevent its operation, a group of subscribers' lines, a group of trunk lines, line switches individual to said subscribers' lines arranged to establish connec- 125 130

tions between said subscribers' lines and said trunk lines only when the shunt is unbroken, means operated when all the trunks are busy to break the shunt around the relay, a connection whereby the relay is operated responsive to the initiation of a call while the shunt is broken, and means controlled by the relay for maintaining the shunt broken independent of the busy or idle condition of the trunks.

18. In a telephone system, a relay normally shunted to prevent its operation, a group of subscribers' lines, a group of trunk lines, line switches individual to said subscribers' lines arranged to establish connections between said subscribers' lines and said trunk lines only when the shunt is unbroken, a chain of relays one for each trunk, connections for operating each relay when its trunk becomes busy, means operated when all of the chain relays have operated for breaking the shunt around the first mentioned relay, connections whereby said first relay is operated responsive to the initiation of a call while the shunt is broken, and means controlled by said first relay for main-

taining the shunt broken independent of the busy or idle condition of the trunks.

19. In a telephone system, a line, a group of trunks accessible thereto, means responsive to a call on said line for connecting the same with an idle trunk of said group, means for sending directing current impulses through said line and the connected trunk, and means operated if an attempt is made to make a call when all of the trunks are busy to prevent the seizure of a trunk even after a trunk becomes available, whereby said impulses are rendered ineffective for directive purposes.

20. In a telephone system, a line, a group of trunks accessible thereto, means for sending current impulses through the line, said impulses being normally effective to establish desired connections from the line, and means automatically operated when all of the trunks are busy to render the impulses ineffective to extend connections even after a trunk becomes idle.

Signed by me at Chicago, Cook County, Illinois, this 4th day of April, 1925.

TALBOT G. MARTIN.
